Primary Examiner — Jeffrey D Asch*Assistant Examiner* — Tracey J Bell(74) *Attorney, Agent, or Firm* — Dorsey & Whitney LLP(57) **CLAIM**

The ornamental design for a parallel surgical guide spacer, as shown and described.

DESCRIPTION

FIG. 1 is a front, left perspective-view of an embodiment of a parallel surgical guide spacer;

FIG. 2 is a left-side view thereof;

FIG. 3 is a right-side view thereof;

FIG. 4 is a top view thereof;

FIG. 5 is a bottom view thereof;

FIG. 6 is a front view thereof;

FIG. 7 is a back view thereof;

FIG. 8 is a front, left perspective-view of another embodiment of a parallel surgical guide spacer;

FIG. 9 is a left-side view thereof;

FIG. 10 is a right-side view thereof;

FIG. 11 is a top view thereof;

FIG. 12 is a bottom view thereof;

FIG. 13 is a front view thereof; and,

FIG. 14 is a back view thereof.

The broken lines illustrate environmental structure and form no part of the embodiment in which they are shown.
